UNITED STATES PATENT OFFICE.

WILLIAM H. MARTIN, OF LOS ANGELES, CALIFORNIA.

ROTARY-BARREL-RACK WAGON.

SPECIFICATION forming part of Letters Patent No. 592,203, dated October 19, 1897.

Application filed May 12, 1897. Serial No. 636,247. (No model.)

To all whom it may concern:

Be it known that I, WILLIAM H. MARTIN, a citizen of the United States, residing at Los Angeles, in the county of Los Angeles and 5 State of California, have invented a new and useful Improvement in Rotary-Barrel-Rack Wagons for Carting Beer-Barrels or other Barrels, of which the following is a specification.

10 My invention relates to improvements in beer-wagons in which the barrels are placed in cradles pivoted in a rotary wheel or wheels; and the object of my invention is to handle the barrels with ease and convenience.

15 The following is a specification of my invention, in which—

Figure 1 is a side view; Fig. 2, an end view.

Similar letters stand for similar parts throughout the different views.

20 A represents the reach-bar on which the rotary wheel or wheels B turn, and is supported by diagonal braces G at either end of said reach-bar A. A frame H passes around said diagonal braces at either end of said 25 reach-bar A, which constitute frames for carrying extra barrels if necessary.

The wheel or wheels B are supplied with cradles C for the reception of barrels E. Said cradles are pivoted to the rotary wheel B, as at D.

F represents a slide-bolt which locks or unlocks the rotary wheel B, said bolt sliding in or out at the end of one of the frame-tubes H.

To unload the barrels, turn the wheel B 35 until the barrel desired attains convenient height. Then press the cradle C inwardly one-fourth turn, which will allow the barrel to drop from cradle.

What I claim as my invention, and desire 40 to secure by Letters Patent of the United States, is—

The combination in a beer-wagon of a rotary barrel-rack wheel or wheels B supplied with pivoted cradles C for the reception 45 of barrels E, said wheel or wheels turning on said reach-bar A, all substantially as described.

W. H. MARTIN.
